TWO-PIECE SHEET METAL WRENCH

Carl P. Ayers, Batavia, Ill.

Application March 17, 1954, Serial No. 416,857

9 Claims. (Cl. 81—130)

The present invention relates to wrenches, more particularly to wrenches of the type commonly called monkey wrenches, and the invention has for an object the provision of a new and improved wrench of this type which is extremely simple in construction and may be manufactured at low cost by mass production methods. Specifically, the present application is a continuation-in-part of my copending application Serial No. 347,911, filed April 10, 1953, now abandoned.

While many arrangements have been heretofore proposed for the construction of monkey wrenches, these arrangements have in general been directed to the provision of relatively heavy cast parts which must be machined to close tolerances to provide a suitable device. Furthermore, these arrangements have necessarily involved a large number of parts, each requiring a separate machining operation with the result that the final cost, as well as the cost of materials, of these arrangements is relatively high and they do not lend themselves to mass production techniques.

Accordingly, it is another object of the present invention to provide a new and improved monkey wrench which is of simplified two-piece construction, is constructed entirely of low cost, light weight metal stampings and yet is of rugged construction and is reliable in its operation.

It is a further object of the present invention to provide a new and improved monkey wrench of sheet metal construction wherein only two metal stampings are employed while providing adjustable interlocking means for holding the jaws of the wrench at any desired spacing.

It is a still further object of the present invention to provide a new and improved monkey wrench of sheet metal construction which is of simplified two-piece construction and which is particularly suited for use with nuts of relatively small size.

Briefly, in accordance with one aspect of the invention, there is provided a sheet metal lower jaw member having lower side wall portions defining a hollow handle portion and having upper side wall portions terminating in overlapping top wall portions which define a lower jaw surface, and a sheet metal upper jaw member of generally U-shaped cross section and having an upper right angle portion defining an upper jaw surface. Opposed apertures are provided in the side walls of the lower jaw member adjacent the lower jaw surface thereof which are adapted to receive the lower portion of the upper jaw member so that the upper jaw member may be slid into the hollow handle portion of the lower jaw member. Cooperating interlocking means on the upper and lower jaw members are provided for holding the upper and lower jaw surfaces in adjustable spaced relation, the interlocking means being disengageable by relative lateral movement of the members, and cooperating means on the contiguous side walls of the upper and lower jaw members are provided for holding the members in interlocked position, these side walls being sufficiently resilient to permit adjustment of the interlocking means. According to a further aspect of the invention, the upper and lower jaw surfaces are arranged at an angle to the handle of the wrench and the interlocking means is positioned below the lower jaw surface to permit nuts of relatively small size to be held by the wrench.

The invention, both as to its organization and method of operation, together with further objects and advan-

tages thereof, will best be understood by reference to the following specification taken in connection with the accompanying drawings in which:

- Fig. 1 is a perspective view of a wrench embodying the features of the present invention, a portion thereof being broken away to show the interlocking means thereof;
- Fig. 2 is a front elevational view, partly in section, of the wrench of Fig. 1 showing the manner in which the parts are assembled;
- Fig. 3 is a left side elevational view of the wrench of Fig. 1;
- Fig. 4 is a sectional elevational view taken along the line 4—4 of Fig. 3;
- Fig. 5 is a cross sectional view taken along the line 5—5 of Fig. 4 assuming that Fig. 4 shows the complete structure;
- Fig. 6 is a view similar to Fig. 5 taken along the line 6—6 of Fig. 4;
- Fig. 7 is a perspective view of a wrench showing an alternative embodiment of the present invention;
- Fig. 8 is a front elevational view similar to Fig. 2 partly in section, of the wrench of Fig. 7 showing the manner in which the parts are assembled;
- Fig. 9 is a right side elevational view of the wrench of Fig. 7;
- Fig. 10 is a partial sectional view taken along the line 10—10 of Fig. 9;
- Fig. 11 is a front elevational view of an alternative embodiment of the invention wherein the jaws of the wrench are arranged at an angle to the handle portion thereof;
- Fig. 12 is a sectional view similar to Fig. 11 and showing the manner in which the parts are assembled;
- Fig. 13 is a left side view of the wrench shown in Fig. 11; and
- Figs. 14 and 15 are sectional views taken along the lines 14—14 and 15—15, respectively of Fig. 11.
- Referring now to the drawings, and more particularly to Figs. 1 to 6, inclusive, thereof, the improved monkey wrench of the present invention is therein illustrated as comprising a lower jaw member, indicated generally at 12, and an upper jaw member, indicated generally at 13. The members 12 and 13 are both of sheet metal construction and may be formed by suitable metal stamping or drawing operations. Thus, the lower jaw member comprises the lower side wall portions 14, 15, 16 and 17 which define a hollow handle portion which may be knurled, as indicated at 18, to provide a suitable gripping surface. The lower jaw member 12 also comprises the upper side wall portions 19 and 20 which extend generally at right angles to the hollow handle portion and terminate in overlapping top wall portions 21 and 22. Thus, as shown in Figs. 4 and 6, side wall portion 19 is turned laterally to form the top wall portion 21, and the side wall portion 20 is turned laterally over the portion 21 to provide the top wall portion 22, the upper surface of the top wall portion 22 acting as a lower jaw surface of the wrench. The end portion 23 of the side wall portion 19 and the end wall portion 24 of the side wall portion 20 are also formed in overlapping relation, as is best illustrated in Fig. 4, so that a rigid, boxlike construction is provided for the jaw portion of the lower jaw member 12. It will be evident that the lower jaw member 12 may be readily formed from sheet metal by a series of suitable stamping operations, as will be well understood by those skilled in the art. It will also be understood that the overlapping portions of the member 13 may be secured together by any suitable means such as spot welding, or the like, so that a rugged jaw construction is provided.

The upper jaw member 13 of the wrench comprises the lower side wall portions 30, 31 and 32 which define an elongated shank portion and also comprises the upper side wall portions 33, 34 and 35 (Fig. 6) which extend generally at right angles to the shank portion of the member 13, the bottom surface of the wall 35 acting as an upper jaw surface. Also, the end portions 37 and 38 of the side wall portions 33 and 34, respectively are formed in overlapping relation so that a boxlike structure is provided for the upper jaw of the wrench. It will be evi-

dent that the member 13 may be formed by a suitable compound action die for deep drawn steel as will be readily understood by those skilled in the art, the end portions 37 and 38 being secured together by a suitable spot welding operation or the like.

In order to permit assembly of the upper and lower jaw members 12 and 13 into a complete wrench unit, the lower jaw member 12 is provided with an aperture 40, in the upper corner thereof adjacent the jaw portion 22, which is sufficiently wide to permit the shank portion 30 of the upper jaw member to be inserted thereto. The side wall portion 17 of the hollow handle portion is also of relatively short length so as to define the aperture 41 which permits the shank portion to extend through the hollow handle portion of the member 12 and to be laterally adjusted relative thereto.

For the purpose of providing additional strength for the lower jaw member, the side wall portions thereof are provided with elongated ridges which function to stiffen the side wall portions of this member. More particularly, the side wall portions 19 and 20 of the member 12 are provided with the stiffening ridges 47 and 48 which provide additional strength for the lower jaw portion of the member 12.

In order to provide means for holding the jaw portions 22 and 35 in adjustable spaced relation, there is provided cooperating interlocking means on the upper and lower jaw members 12 and 13 which function to hold the jaws in any desired spacing. More particularly, the lower jaw portion 22 is provided with a rearwardly extending projection or tongue 43 which extends into the opening 40 and is adapted to interlock with any one of a plurality of slots 44 formed in the side wall portion 32 of the member 13.

In order to hold the jaw members in interlocked relation when the desired spacing between jaw members has been attained, there is provided cooperating means on the contiguous side wall portions of the upper and lower jaw members for holding these members in interlocked relationship. More particularly, the stiffening ridges 47 and 48 in the side wall portions of the member 12 are extended into the hollow handle portion of the member 12 in generally parallel relation thereto. In addition, small detents or projections 50 and 51 are provided in the side wall portions 30 and 31 of the member 13, these projections, or detents, extending outwardly being adapted to fit into the lower portions of the stiffening ridges 47 and 48 when the jaw members are assembled in interlocking relation as best illustrated in Fig. 5.

Considering now the manner in which the wrench may be assembled and used, the shank portion of the member 13 is first inserted into the top aperture 40 in the member 12, this shank portion being adapted telescopically to fit within the hollow handle portion of the member 12. In so doing, the projections 50 and 51 press against the side wall portions 14 and 16 of the member 12. However, the side wall portions of the members 12 and 13 are sufficiently resilient to permit the member 13 to be inserted into the hollow handle portion of the member 12 by a force fit. The member 13 is inserted into the member 12 at an angle thereto, as illustrated in Fig. 2, until the desired spacing between the jaw surfaces is obtained, at which point the projection 43 is inserted into the corresponding one of the grooves 44 so that the members 12 and 13 are held in interlocking relationship. The shank portion member 13 is then pivoted or moved laterally relative to the member 12 by a simple gripping or squeezing of the shank portion of the member 13 into the hollow handle portion of the member 12 so that these members are parallel to each other. In this latter position, the projections 50 and 51 snap into the lower portions of the ridges 47 and 48 so that the members 12 and 13 are held in interlocked relationship with the desired spacing between the jaw surfaces thereof. If it is desired to adjust the wrench to accommodate a different size nut, the upper jaw member 13 is merely moved laterally as by pivoting about the upper edge 59 of the side wall 15, until the projection 43 is disengaged from the member 13, and the member 13 is then adjusted to the new position after which the members are moved or pivoted laterally so that the projections 50 and 51 again rest within the ridges 47 and 48.

It will be noted that the member 13, when inserted into the hollow handle portion of the member 12, is so arranged that the rear edges of the side wall 32 are urged

into engagement with the side wall 15 of the member 12 when the wrench is actually used to tighten a nut. Accordingly, the adjustment of the wrench is not disturbed during use but instead the leverage set up during use actually aids the interlocking action between the members 12 and 13. However, the wrench may be readily "broken" by exerting a force in the opposite direction so that adjustment of the wrench may be conveniently made.

In the alternative embodiment shown in Figs. 7 to 10, inclusive, there is shown a wrench which is of generally similar sheet metal construction and corresponding elements thereof have been given the same reference numerals as those employed in Figs. 1 to 6, inclusive. Referring to this alternative embodiment, the upper and lower jaw members are interlocked by providing the rearwardly extending lugs or projections 55 and 56 on the bottom edge portions of the side walls 30 and 31 of the member 13. The side wall 15 of the member 12 is also provided with cooperating sets of apertures 57 and 58 which are adapted to receive the projections 55 and 56 on the member 13. With this arrangement, the shank portion of the member 13 is inserted into the top opening 40 of the member 12 in a manner similar to that described above in connection with the wrench shown in Fig. 1, and the projections 55 and 56 are inserted into the corresponding apertures 57 and 58 to give the desired jaw spacing. However, in the alternative embodiment, adjustment of the jaw spacing may be made by pivoting the member 13 against the upper edge 59 of the side wall 15 by an amount sufficient to remove the projections 55 and 56 from the corresponding apertures 57 and 58, after which the member 13 may be moved longitudinally relative to the member 12 until the projections 55 and 56 enter the desired set of adjusting apertures.

In some instances it may be desirable to make the ridges 47 and 48 somewhat wider than the projections 50 and 51 so as to permit sufficient lateral movement between the members 12 and 13 to accomplish the above described adjustment of the jaw spacing. With such an arrangement the projections 50 and 51 function to retain the member 13 within the hollow handle portion of the member 12, the particular adjustment of the jaw spacing being maintained by the gripping action of the operator when the wrench is not actually in use.

In a further alternative embodiment of the invention shown in Figs. 11 to 15, inclusive, there is shown a wrench which is of generally similar sheet metal construction and is particularly suitable for use with nuts of relatively small sizes. Referring to this embodiment, the upper jaw member 70 is provided with top flange portions 71 and 72 which are secured together by a suitable spot welding operation, or the like, as indicated at 73, to provide an enclosed upper jaw for the wrench. The bottom portion of the upper member 70 is provided with indentations 74 which cooperate with grooves 75 in the lower jaw member 76 as described in detail above in connection with the other embodiments of the invention. In the embodiment shown in Figs. 11 to 15, inclusive, the upper jaw surface 77 of the upper member 70 and the lower jaw surface 78 of the bottom member 76 are positioned at an angle to the handle portion of the wrench. Furthermore, the side wall 79 of the jaw member 76 is formed in a rectangular boxlike arrangement to provide an intermediate partition wall 80 which is positioned below the jaw surface 78 and is provided with a tongue portion 81 which is adapted to interlock with the openings 82 in the upper jaw member 70. The other side wall 83 of the jaw member 76 is provided with a top flange portion 84 which is secured to the top and side of the boxlike structure formed from the side wall 79 so that an extremely rugged and durable lower jaw arrangement is provided. By positioning the jaw surfaces 77 and 78 at an angle to the handle of the wrench and by locating the tongue 81 substantially below the lower jaw surface 78 a wrench construction is provided which is particularly suited for gripping nuts of small sizes. This will be readily apparent when it is realized that the upper jaw member 70 pivots at a point which falls on a line perpendicular to the upper jaw surface 77, this perpendicular line being a substantial distance from the inside corner of the upper jaw member. As a result, there is no tendency for the wrench members to open up when nuts of small sizes are held and force is applied to the lower jaw member 76 to tighten the nut. This

is because the resultant force on the upper jaw member 70 is applied inside the above described perpendicular line so that this force actually assists in holding the upper and lower jaw members together instead of tending to force the members apart. In other respects the embodiment shown in Figs. 11 to 15, inclusive, functions in a manner similar to that described in detail above to provide a wrench which may be adjusted to fit nuts of standard sizes.

From the foregoing description it will be evident that the present invention provides a monkey wrench of sheet metal construction which is extremely simple in design and may be manufactured at low cost by means of metal stampings which are readily produced by mass production methods. Furthermore, the two-piece construction of the wrench affords interlocking means whereby the upper and lower jaws of the wrench may be held in adjustable spaced relationship while providing suitable detent means for holding the members in the desired spacing. In addition a boxlike construction of the jaw portions of the wrench is employed to produce an extremely rugged structure while providing the simplicity and low cost of sheet metal construction.

While there have been described what are considered to be the preferred embodiments of the invention, it will be understood that various modifications may be made therein which are within the true spirit and scope of the invention as defined in the appended claims.

What is claimed as new and is desired to be secured by Letters Patent of the United States is:

1. A monkey wrench of sheet metal construction, comprising a sheet metal lower jaw member having lower side walls defining a hollow handle portion and having overlapping top wall portions defining a lower jaw surface, a sheet metal upper jaw member of generally U-shaped cross section adapted telescopically to slide between the side walls of said lower jaw member into the hollow handle portion thereof, said upper jaw member having an upper right angle portion defining an upper jaw surface, and cooperating interlocking means on the contiguous edges of said upper and lower jaw members for adjustably holding said upper and lower jaw surfaces in spaced relation.

2. A monkey wrench of sheet metal construction, comprising a sheet metal lower jaw member having lower side wall portions defining a hollow handle portion and having upper side wall portions terminating in overlapping top wall portions which define a lower jaw surface, a sheet metal upper jaw member of generally U-shaped cross section and having an upper right angle portion defining an upper jaw surface, means defining opposed apertures in the side walls of said lower jaw member adapted to receive the lower portion of said upper jaw member, whereby said upper jaw member may be slid into the hollow handle portion of said lower jaw member, and cooperating interlocking means on said upper and lower jaw members for adjustably maintaining said upper and lower jaw surfaces in spaced relation.

3. A monkey wrench of sheet metal construction, comprising a sheet metal lower jaw member having lower side wall portions defining a hollow handle portion and having upper side wall portions terminating in overlapping top wall portions which define a lower jaw surface, a sheet metal upper jaw member of generally U-shaped cross section and having an upper right angle portion defining an upper jaw surface, means defining opposed apertures in the side walls of said lower jaw member adapted to receive the lower portion of said upper jaw member, whereby said upper jaw member may be slid into the hollow handle portion of said lower jaw member, and cooperating interlocking means on said upper and lower jaw members for adjustably maintaining said upper and lower jaw surfaces in spaced relation, said last named means comprising a projection on said top wall portions extending into said upper jaw member receiving aperture, and means defining a plurality of apertures in the opposing side wall of said upper jaw member for receiving said projections, whereby said upper and lower jaw surfaces may be adjustably held in spaced relation.

4. A monkey wrench of sheet metal construction, comprising a sheet metal lower jaw member having lower side wall portions defining a hollow handle portion and having upper side wall portions terminating in overlapping top wall portions which define a lower jaw surface, a sheet metal upper jaw member of generally U-

shaped cross section and, having an upper right angle portion defining an upper jaw surface, means defining opposed apertures in the side walls of said lower jaw member adapted to receive the lower portion of said upper jaw member, whereby said upper jaw member may be slid into the hollow handle portion of said lower jaw member, and cooperating interlocking means on said upper and lower jaw members for adjustably maintaining said upper and lower jaw surfaces in spaced relation, said last named means comprising rearwardly extending side wall projections at the bottom of said upper jaw member, and means defining a plurality of apertures in the rear wall of said hollow handle portion for receiving said projections.

5. A monkey wrench of sheet metal construction, comprising a sheet metal lower jaw member having lower side wall portions defining a hollow handle portion and having upper side wall portions terminating in overlapping top wall portions which define a lower jaw surface, a channel-shaped sheet metal upper jaw member having an upper right angle portion defining an upper jaw surface, means defining opposed apertures in the side walls of said lower jaw member adapted to receive the lower portion of said upper jaw member, cooperating means on said upper and lower jaw members for adjusting the relative spacing of said upper and lower jaw surfaces, and cooperating retaining means on the contiguous side walls of said upper and lower jaw members for holding said members in adjusted position.

10. 6. A monkey wrench, comprising a hollow sheet metal lower jaw member having a handle portion and a right angle portion defining a lower jaw, means defining an aperture in the top wall of said lower jaw member which provides access to the interior thereof, a sheet metal upper jaw member provided with a right angle portion defining an upper jaw and a lower portion adapted to extend through said aperture into the hollow handle portion of said lower jaw member, cooperating interlocking means on said upper and lower jaw members for holding said upper and lower jaws in adjustable spaced relation, said interlocking means being disengageable by relative lateral movement of said members, and cooperating means on the contiguous side walls of said upper and lower jaw members for restraining lateral relative movement of said members while permitting adjustment of said interlocking means.

15. 7. A monkey wrench comprising a hollow sheet metal lower jaw member having a handle portion and a right angle portion defining a lower jaw, means defining an aperture in the top wall of said lower jaw member which provides access to the interior thereof, a sheet metal upper jaw member provided with a right angle portion defining an upper jaw and a lower portion adapted to extend through said aperture into the hollow handle portion of said lower jaw member, cooperating interlocking means on said upper and lower jaw members for holding said upper and lower jaws in adjustable spaced relation, said interlocking means being disengageable by relative lateral movement of said members, and detent means on the contiguous side walls of said upper and lower jaw members for holding said member in interlocked position, said contiguous side walls being sufficiently resilient to permit displacement of said detent means during adjustment of said interlocking means.

20. 8. A monkey wrench, comprising a hollow sheet metal lower jaw member having a handle portion and a lower jaw portion extending transversely therefrom at an angle less than ninety degrees with respect to said handle portion, means defining an aperture in the top wall of said lower jaw member which provides access to the interior thereof, a sheet metal upper jaw member provided with an upper jaw portion generally parallel to said lower jaw portion and having a shank portion adapted to extend through said aperture into the hollow handle portion of said lower jaw member, a rearwardly extending tongue on said lower member spaced below the jaw surface of said lower jaw portion and adapted to cooperate with corresponding apertures in said upper jaw member to hold said upper and lower jaws in adjustable spaced relation, said tongue being disengageable from one of said apertures by relative lateral movement of said members, and cooperating means on the contiguous side walls of said upper and lower members for restraining lateral relative movement of said members while permitting adjust-

ment of said tongue to vary the spacing of said upper and lower jaw portions.

9. A monkey wrench of sheet metal construction, comprising a sheet metal lower jaw member having lower side walls defining a hollow handle portion and having overlapping top wall portions defining a lower jaw surface, said lower jaw surface extending at an angle less than ninety degrees with respect to said handle portion, a sheet metal upper jaw member of generally U-shaped cross section adapted telescopically to slide between the side walls of said lower jaw member into the hollow handle portion thereof, said upper jaw member having an upper transverse portion defining an upper jaw surface generally parallel to said lower jaw surface, and co-

5
10
8
operating interlocking means on the contiguous edges of said upper and lower jaw members for adjustably holding said upper and lower jaw surfaces in spaced relation.
